UNITED STATES PATENT OFFICE.

EDWARD C. MADARY, OF TRAVERSE CITY, MICHIGAN.

INCUBATOR AND BROODER.

1,119,090.

Specification of Letters Patent.

Patented Dec. 1, 1914.

Application filed June 29, 1912. Serial No. 706,688.

To all whom it may concern:

Be it known that I, EDWARD C. MADARY, a citizen of the United States, residing at Traverse City, in the county of Grand 5 Traverse and State of Michigan, have invented a new and useful Incubator and Brooder, of which the following is a specification.

This invention relates to improvements in 10 a combined incubator and brooder.

The primary object of the invention is to provide an incubator and brooder of novel construction, and provided with unique means for heating and ventilating the incubation and brooding compartments.

With the foregoing and other objects in view which will appear as the description proceeds, the invention resides in the combination and arrangement of parts and in 20 the details of construction hereinafter described and claimed, it being understood that changes in the precise embodiment of the invention herein disclosed, can be made within the scope of what is claimed, without 25 departing from the spirit of the invention.

In the drawings: Figure 1 is a vertical section. Fig. 2 is a horizontal section. Fig. 3 is a transverse section.

In the drawings, 10 designates a double 30 walled case or cabinet which is mounted upon legs 11, the cabinet having an upper incubation compartment or chamber A and a lower brooding or nursery compartment or chamber B having air inlets in its walls. 35 Egg trays 12 are supported slightly above the bottom of the incubation compartment, and the said bottom is provided with an opening at one end to establish communication between the brooding compartment and 40 superposed incubation compartment. An inclined plate or apron 16 is secured to the end wall 15 of the cabinet below the opening between the said end wall and the bottom of the compartment A to permit the chicks to 45 descend into the compartment B, the compartment B having a door 17 at one side provided with a glass panel.

The compartments are ventilated by perforated outlet and inlet pipes 18 and 19, 50 respectively. The outlet pipes or conduits 19 are disposed between the egg trays 12 and the bottom of the incubation compartment to carry off the foul air from directly below the trays, and the inlet pipes 18 are 55 disposed at the top of the incubation com-

partment, the pipes 18 and 19 extending longitudinally within the cabinet and having their end portions 22 and 21, respectively, extended upwardly and downwardly within the walls of the end 24 of the cabinet and 60 opening through the outer wall.

Arranged within the upper portion of the incubation compartment are a plurality of incandescent electric lights 26 and arranged within the brooding compartments 65 27, said lights being partially incased by the lower shields 28, which prevent the heat and light from the lamps from being projected directly downward, the shields and lights being secured to the 70 side walls of the cabinet. The respective lights 26 and 27 are regulated by the electric thermostats 29 and 30, the thermostat 29 being positioned in the incubation compartment and the thermostat 30 in the 75 brooding compartment. In this manner the heat in the two compartments is maintained at an even temperature.

The cloth diffusing diaphragm 32 is disposed between the lights 26, and the egg tray. 80 The compartment above the diaphragm receives the heat, moisture and fresh air and evenly distributes the admixture within the egg chamber after it is filtered through the diaphragm. The proper moisture is produced by the humidor 31, shown in my Patent No. 964,442.

The end 15 of the cabinet or case adjoining the opening in the bottom of the incubation chamber, or the partition between 90 the two chambers, is provided with doors 33 for the upper or incubation compartment, to enable the trays to be readily inserted and withdrawn, and to otherwise permit access to be had into the incubation chamber. 95

It will be evident that the diffusing diaphragm 32 serves to diffuse the light, heat and humidified air in the upper portion of the incubation compartment, descending to the egg trays, the foul air being drawn off 100 from below the egg trays through the discharge or eduction pipes or conduits 18. It is also to be noted that the air rising from the brooding compartment will pass through the opening in the bottom of the incubation 105 compartment and will then be drawn off through the discharge or eduction pipes 18. Both sets of pipes or heaters 26 and 27 may be in operation at the same time, or either set of lights or heaters may be operated 110

independent of the other set, whereby the compartments may be effectively heated and ventilated.

What is claimed is:—

- 5 1. In an incubator, a case having a brooding chamber provided with air inlets, and a superimposed incubation chamber, the incubation chamber bottom having an opening at one end leading to the brooding chamber,
- 10 an egg tray supported slightly above the bottom of the incubation chamber, air inlet means leading to the upper portion of the incubation chamber, air eduction means leading from between the egg tray and incubation chamber bottom, and independent heating means within the brooding chamber and the upper portion of the incubation chamber.
- 15 2. In an incubator, a case having a brooding chamber provided with air inlets, and a superimposed incubation chamber, the in-

cubation chamber bottom having an opening leading to the brooding chamber, an egg tray supported slightly above the incubation chamber bottom, a diffusing diaphragm between the top and bottom of the incubation chamber, inlet and outlet conduits above the said diaphragm and between the egg tray and incubation chamber bottom, respectively, and having their outer ends directed downwardly and upwardly, respectively, and independent heaters above the said diaphragm and within the brooding chamber.

In testimony that I claim the foregoing as my own, I have hereto affixed my signature in the presence of two witnesses.

EDWARD C. MADARY.
